CLAIM

I claim the ornamental design for a mobile terminal, as shown and described.

DESCRIPTION

FIG. 1 is a front-left-top perspective view of a mobile terminal of the present invention;

FIG. 2 is a rear-right-top perspective view thereof;

FIG. 3 is a rear-left-bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines shown in the drawings illustrate portions of the mobile terminal that form no part of the claimed design. Additionally, the unevenly broken lines in the drawings define the limits of the claimed design.
